UNITED STATES PATENT OFFICE.

JOHN C. DODGE, OF BROOKLYN, NEW YORK.

IMPROVEMENT IN RING-AND-TRAVELER SPINNING-FRAMES.

Specification forming part of Letters Patent No. 13,187, dated June 21, 1864.

To all whom it may concern:

Be it known that I, JOHN C. DODGE, a resident of Brooklyn, of the county of Kings and State of New York, have invented a new and useful Improvement in Spinning Mechanism; and I do hereby declare the same to be fully described in the following specification and represented in the accompanying drawings, of which—

Figure 1 is a top view, Fig. 2 a side elevation, and Fig. 3 a vertical section, of a traveler-ring having my invention, it being an improvement on that for which Letters Patent No. 8,683 were granted on the 27th day of January, 1852, to my late son, George H. Dodge, such patent having been duly assigned to me, as will appear by the records of the United States Patent Office.

The invention of the said George H. Dodge consisted in a projection or standard erected on the ring-supporting plate or rail of the ring-and-traveler spinning-machine and close against and so as to extend both above and below the path of the traveler, the projection being arranged so near the ring as to enable the traveler while in motion not only to clear it, but to throw against it any waste or filaments which may have accumulated on the traveler. The object of such invention was to detach the said waste or filaments from the traveler.

My invention is an improved mode of combining the waste-detacher or projection with the ring of the traveler—that is to say, instead of erecting such detacher and fixing it to the supporting plate or rail of the ring, whereby it shall remain on and be fixed to such plate or rail while the ring is removed from the plate or rail, as well as while the ring is in place thereon, (the ring being usually supported within a socket or round hole formed or through the plate or rail,) I combine it with or fix it directly to the ring, so as to be movable with such ring from such plate or rail.

In the drawings, D denotes the ring; C, the traveler, and B the waste-detacher or stand-

ard, the latter being represented as fastened to the circumference of the ring and below the flange or part a, on which the traveler is placed and runs. For this purpose I arrange the tenon a' of the standard B so as to project from it horizontally, in order that such tenon may be inserted in a hole, b, made through the ring. The tenon may be fixed in the ring-hole either by "upsetting" the inner end of the tenon or by means of solder applied thereto and to the ring.

It is not an uncommon occurrence for a detacher to become broken from the rail or bent or otherwise injured. Under such circumstances, when the waste-detacher is fastened to the ring-rail or supporter the operation of the whole spinning-machine will have to be arrested during the period which may be required to remove the injured detacher and either supply its place with a new one or make the proper repair. But with the waste-detacher affixed directly to and supported by the ring the spinning-frame does not require stoppage for repair or replacement of the detacher, as the ring of the broken or injured detacher can readily be lifted out of its place in the ring-rail, and another ring carrying another detacher can be immediately substituted for it, and this while the spinning-frame may be in action.

I do not herein claim the combination of a standard or waste-detacher with the ring and traveler in the manner represented and described in the said patent to which reference has heretofore been made.

What I do claim as my invention or improvement is—

The connection of the waste-detacher with the ring so as to be attached to it, and with it be removable from the ring-rail or socket-plate, the whole being substantially as specified.

JOHN C. DODGE.
